APPARATUS FOR PRESSING AND STACKING
PACKAGES OF PLYWOOD AND THE LIKE

Ray C. Demler, Tacoma, Wash., assignor to International Packaging Corporation, Tacoma, Wash., a corporation of Washington

Application June 9, 1952, Serial No. 292,569

19 Claims. (Cl. 53—45)

1

The present invention relates to apparatus for handling wrapped packages of sheet material such as plywood and the like.

The primary object of the present invention is the provision of apparatus for handling freshly wrapped packages of sheet panels in a completely automatic manner, so that the individual packages are received from a wrapping machine or the like and stacked in superimposed relation, with top pressure being applied to the individual packages to take the warp out of the packages, and side pressure and heat being applied to insure that the freshly wrapped and sealed package does not come undone while being stacked.

A still further object is the provision of apparatus for stacking individual packages of sheet material and discharging the same in stacks suitable for shipment, all in a completely automatic manner.

A still further object is to provide apparatus for handling freshly wrapped packages of sheet material wherein wax is automatically applied to the upper surfaces of the individual packages to obviate damage to the packages through frictional contact with each other during the stacking and subsequent handling operation, with means being provided for pressing, heating, stacking and discharging the packages in predetermined stack heights.

A further object is to provide apparatus for handling packages of sheet material wherein the sequence of operations of pressing, heating, stacking and discharging is controlled by means responsive to the movement of the packages through the apparatus.

With the foregoing and other objects in view, the invention will now be more fully described with reference to the accompanying drawings wherein:

Figure 1 is a side elevation of the apparatus of the present invention;

Figure 2 is a top plan view;

Figures 3 and 3a constitute an enlarged detailed sectional view of the entire machine and are taken substantially along line 3—3 of Figure 2;

Figure 4 is a vertical sectional view taken along line 4—4 of Figure 3a;

Figure 5 is a vertical sectional view taken along line 5—5 of Figure 3a;

Figure 6 is a horizontal sectional view taken along line 6—6 of Figure 1 of the elevator platform and the side delivery conveyors;

Figure 7 is a sectional view substantially along the line 7—7 of Figure 6, and illustrates the transfer mechanism for removing the stack of packages from the elevator; and

Figure 8 is a detail of the switches, motors, and circuits associated with the apparatus, with

the travel path of the package being indicated by broken lines.

General description of the apparatus

5 The apparatus of the present invention is adapted for use in connection with wrapping machines of the type described and claimed in my co-pending application Serial No. 198,711, filed December 1, 1950. It is to be understood, however, that its applicability is not to be so narrowly limited, since the apparatus can be used in connection with any wrapping machine, or to receive previously wrapped packages from a conveyor wherein stacking of the packages in predetermined number is desired.

In the machine of my co-pending application Serial No. 198,711, a stack of plywood or other such sheet material has top and bottom sheets of wrapping paper applied after which the sides

20 and ends of the wrapping paper are glued and folded, whereupon the package is discharged. The machine of the present invention can be most advantageously employed in connection with such a mechanism, and to accomplish this end, 25 the improved press and stacker assembly of the present invention is connected to such a machine by a series of upper and lower conveyors to receive the wrapped packages and deliver them to a pair of spaced supporting members, whereupon

30 the package is dropped to an elevator disposed beneath the supporting rails, whereupon pressure is applied to the top of the package and heat and pressure are applied to the sides and ends, the pressure and heat being applied to the sides and

35 ends of the package to insure the rapid drying of the freshly glued wrappings. When a predetermined number of packages has been deposited on the elevator, the stack of packages is discharged laterally from the elevator, whereupon 40 the elevator returns to its full up position beneath the pair of supporting rails, with all the sequence of operations being controlled by the motion of the packages and the descent of the elevator.

Referring now in more detail to the drawings, 45 12 generally designates the press and stacker assembly of the present invention which is comprised of a series of upstanding channel members 14, transverse members 16 and longitudinal members 18 which constitute the supporting framework.

When the press and stacker assembly is to be employed in connection with the packaging machine of my co-pending application, previously referred to, upper and lower endless conveyors 20 and 22 of the type shown in Figure 3 are preferably employed to deliver the wrapped package to the front end of the press and stacker assembly 42. An additional conveyor roller 24, in con-

junction with the smaller rollers generally designated at 26, supports the package in its progress into the press and stacker assembly.

In this arrangement, a wax applying, hollow roller 27 is freely journaled above the moving package at the front end of the stacker to deposit wax on the upper surface of each package to prevent tearing through frictional contact. The roller 27 is counterweighted as seen at 28, and is filled with a suitable dry wax. The perforation 30 in the periphery of the roller 27 provides a point of egress for the dry wax to be deposited on the upper surface of the moving package P. It will be observed that with this arrangement the perforation 30 is not in position to deposit wax except when the package is in contact with the periphery of the roller 27 rotating it against the counterweight 28 to produce a complete revolution thereof. According to this arrangement wastage of the dry wax from the storage chamber within roller 27 is prevented.

As previously indicated, the press and stacker assembly of the present invention may be employed in connection with any type packaging machine or may be used to stack packages in stacks of predetermined number from any source. Figures 1 and 2 show the press and stacker assembly associated with conventional conveyor rollers 32, 33 and 34 to deliver the packages to the press and stacker 12. However, the conveying mechanism as shown and described in connection with Figure 3 is preferred, since it is desirable to have upper and lower endless conveyors for the package to obviate, insofar as possible, any distortions or warping which inevitably take place wherever material such as plywood is being handled.

The front end of the package P, after leaving the aforementioned conveyors, enters the press and stacker assembly and is supported by a pair of pivotally mounted rail members 36 and 38 (shown in detail in Figures 4 and 5). Rails 36 and 38 are integral with the side pressure heating pads 40 and 42 to be hereinafter more fully described. Pads 40 and 42, upon which the rails 36 and 38 are mounted, are supported by a series of depending members 44 and 44', which, in turn, are pivotally mounted on each side of the apparatus at 46 and 46' to the transverse channel frame members 16.

Referring to Figure 5, a pair of the members 44 and 44' are shown pivotally connected at their upper ends at 48 and 48' to a pair of connecting arms 50 and 50'. Each of the connecting arms 50 and 50' extends inwardly and is pivotally connected at 52 and 52' to a pair of radially extending links 54 and 54' welded or otherwise secured to a rotatable shaft 55 journaled in the bearing blocks 58 mounted medially on the transverse members 16.

Shaft 55 extends between cross members 16' and 16'', and is supported by bearing blocks mounted on members 16', 16'' and 16''', and the above described linkage arrangement is duplicated at these points to insure a simultaneous movement of the pressure heating pads 40 and 42 throughout their length.

The arcuate movement of heating pads 40 and 42 through the above described linkage arrangement is achieved by the rotation of the longitudinal shaft 55 by means of radially extending rocker arms 56 welded or otherwise secured at their lower ends to the shaft 55, and pivotally connected at their upper ends to the piston rods 60 extending from a pair of angularly disposed air cylinders 59, which are pivotally mounted on the

side longitudinal frame members 18. Two such air cylinders 59 are shown in Figure 1 as being sufficient to displace rails 36 and 38, with the associated pads 40 and 42, from contact with the wrapped package P to be pressed and stacked.

The wrapped package P is moved along the rails 36 and 38 at each side of the assembly until the rear of the package contacts a bumper bar assembly, generally indicated at 64, which is adjustably mounted on the longitudinal channel member 18 extending medially of the press and stacker assembly. Bumper bar 64 may be adjusted to any position along the channel member 18 by means of the set screw 66 (Figures 4 and 6). The channel member 18 runs the full length of the press and stacker assembly, thereby permitting a variety of adjustments so that the apparatus can be employed with packages of considerable variance in length.

Secured to the depending free end of the bumper bar assembly 64 is an end presser plate 68 having the strip heaters 69 secured thereto. The function of this member will be described in more detail in connection with the side presser plates 40 and 42. Side presser plates 40 and 42 are likewise provided with strip heating elements 70, as seen in Figure 1.

As soon as the wrapped package P contacts the bumper bar 64, the rails 36 and 38 supporting the package on each side thereof are displaced laterally by means of the cylinders 59 and associated piston rods 60 which move in response to limit switches on the bumper bar 64 to be subsequently described, permitting the package to drop to the surface of the elevator 72. The elevator 72 is comprised of a bed, constructed from end channel members 133 and longitudinal channel members 135, which is provided with a series of transverse conveyor rollers 74 mounted thereon to facilitate the sidewise discharge of the packages. The elevator assembly 72 is slidably mounted on the upright channel frame members 14 by means of the sliding guides 74 at each end of the elevator assembly (Figure 3a). The elevator is supported by means of chains 76 and 78 which are led around the sprockets 80 and 82, respectively. The free ends of chains 76 and 78 are counterweighted as shown in Figures 3 and 3a at 84 and 86. Sprockets 80 and 82 are driven by means of the chain 88 which extends longitudinally of the machine. Chain 88 drives sprockets mounted on the same shaft supporting the sprockets 80 and 82. Reversible motor 90 is suitably mounted on the rear vertical channel member 14 and by means of a series of reduction sprockets 92, 93 and 94 drives the endless chain 88. A magnetic brake 96 is associated with the reversible motor 90 to insure accurate start and stop control for the elevator assembly 72.

In order to apply pressure to the top of each package to take the warp out of the package as it is being dropped from the supporting rails 36 and 38 to the elevator 72, a pair of top pressure plates 98 and 100 are provided, as can be seen in Figure 5. Top pressure plates 98 and 100 depend from and are supported by a series of piston rods 102 and 103. Rods 102 and 103 are associated with air cylinders 104 and 104', which are secured to channel members extending above the transverse channel frame members 16' and 16''. Piston rods 102 and 103 extend through supporting bushing members 110 and 110', which are secured to the transverse channel members 16' and 16''.

A front end pressure plate 112 (Figures 2 and

3) extends transversely of the machine, and is mounted on a pair of piston rods 114 associated with air cylinders 116, these members being mounted on channel members extending transversely of the machine at the front end thereof.

The bed of the elevator 72 is provided with a series of transverse roller conveyors 74, as previously indicated. Also mounted on the elevator bed 72 is a pusher discharge assembly 118, as seen in Figures 6 and 7. The pusher bar assembly 118 is comprised of a pair of double sheaves 120 and 122 journaled on the free ends of the member 124. Pusher bar 126 is movable by means of a connecting cable 128 extending around sheaves 120 and 122 and over the sheaves 129 and 129' secured to the bed of the elevator. The cable 128 is led from the sheave 129 around a further sheave 130 journaled to one of the end channel members 133, constituting part of the elevator frame, from whence it is led around sheave 132 mounted on the free end of piston 134, shown in dotted lines in its extended position in Figure 7. From sheave 132 the cable 128 is led to its point of attachment 137 on the channel frame member 125 to which the sheave 130 is secured. The other free end of cable 128 is led over sheave 129' and around the double sheave 132 mounted on piston 134 to a point of attachment 136 on one of the elevator bed channel frame members 135.

A second series of transverse roller conveyors 138 is secured to a frame 139 similar to the elevator bed and which is rigidly mounted to the floor of the room or the area wherein the apparatus is to be employed, in such a position that when the elevator 72 is in its lowermost position, the two sets of roller conveyors 74 and 138 form a continuous conveying means, as shown in Figure 6.

Mode of operation

As the wrapped package P enters the press and stacker assembly 42 from the form of conveyors shown in either Figures 2 or 3, the supporting side rails 36 and 38 are in the position shown in Figure 4 to receive the wrapped package. The conveyors 20, 22 or 32, 33, 34 move the package along the rails 36 and 38 until the front end of the package contacts the bumper bar assembly 64. The forward motion of the package is stopped by the bumper bar assembly.

Mounted on the bumper bar assembly are the limit switches 140 and 142 which control solenoid air valves 144, 145 and 146, shown diagrammatically in Figure 8. Limit switch 142 controls the down cycle of the stacker elevator 72 in one of its circuits. When the stacker elevator 72 is empty, manual control switch 148 is off and the down circuit cut so that the elevator will remain in the total up position to receive the first package. As the package P contacts bumper bar assembly 64, limit switches 140 and 142 mounted thereon are also contacted by the package. Limit switch 140 is normally open and, upon being contacted by the package, the circuit is completed to the solenoid air valves 144, 145 and 146. Solenoid air valve 144 controls the air pressure to air cylinders 59, and upon completion of the circuit the valves admit air under pressure to these cylinders, whereupon the pistons 60 are retracted into cylinders 59 to pivot rocker arms 56, and the associated rails 36 and 38 to the position shown in Figure 5, thereby permitting the package to drop down upon the rollers 74 of the elevator assembly 72. At the same time the rails 36, 38 are laterally pivoted, the circuit to solenoid

air valve 145 is completed through limit switch 140. Solenoid air valve 145 controls the air pressure to the cylinders 104 and 104' which control the movement of the top presser bars 98, 100 by means of the pistons 102, 103. The normal position of the top presser bars is up and out of contact with the package, but upon actuation of limit switch 140, solenoid air valve 145 delivers air under pressure to the cylinders 104, causing pistons 102, 103 to descend so as to contact the top edges of the package with the presser bars 98 and 100. The purpose of the top presser plates 98, 100, as previously stated, is to take the warp out of the wrapped package, so that even stacking can be effected.

Simultaneously with the completion of the circuits to solenoid air valves 144 and 145 through limit switch 140, the circuit is completed to solenoid air valve 146 which controls the delivery of air to the cylinders 116. Upon actuation of the limit switch 140 therefor, air is delivered to the cylinders 116 so as to retract pistons 114 and the associated front presser bar 112. Simultaneously with the actuation of solenoid air valves 144, 145 and 146, limit switch 142 is reversed by contact with the front end of the package. Manual control switch 148 is moved to the "on" position as soon as the first package is deposited on the elevator. This control switch remains in the "on" position for all succeeding packages of the same size. Switch 148 completes a circuit to the reversible motor 90, and the elevator is lowered until the top surface of the package P clears limit switches 140 and 142 which, it will be observed, constitutes the depth of one package. Upon clearing limit switches 140 and 142, limit switch 142 is reset breaking the circuit to the motor 90. By means of magnetic brake 91 elevator 72 is instantaneously stopped after dropping the depth of one package. During the descent of the elevator top presser bars 98 and 100 are in contact with the upper side edges of the top package with a force greater than the speed of the descent of the elevator.

Limit switch 142 is cleared by the front end of the package at the same time as limit switch 140. Limit switch 140 being normally open, the circuit is broken to the solenoid air valves 144, 145 and 146, reversing the direction of these valves, causing the top presser bars 98 and 100 to be retracted from contact with the package, and the side presser plates 40 and 42 to be swung into contact with the sides of the package which has just been deposited on the elevator and leaving the guide rails in position to receive the next succeeding package while pressure is being exerted on the sides of the uppermost package by means of the pads 40 and 42, as shown in Fig. 4.

At the same time, front end presser bar 112 is thrust outwardly into contact with the front end of the package, forcing the package against the rear presser bar 68 which is integral with the bumper bar assembly 64. Front presser bar 112, the rear presser bar 68, and side presser plates 40 and 42 are all provided with strip heaters to insure proper sealing of the package in cases where it is received directly from a wrapping machine. These members supply heat to the sides and ends of the package until the following package is received on the rails 36 and 38 and strikes the limit switches 140 and 142, after which the above described cycle of operations is repeated, with the elevator dropping the depth

of one package as each succeeding package is received thereon.

When the stacker elevator has a complete load of packages, and is one half the depth of a package from its total down position, cam surface 153 on the side of the elevator drive chain 88 (the chain synchronizes the front and back end shafts) closes limit switch 152. The arm 151 of limit switch 152 is raised by the cam surface 153. As the next package passes through the conveyors leading to the stacker and presser, the limit switch 154 is closed, and the elevator down circuit through limit switch 152 is completed so that the elevator moves to total down position, leaving the topmost package in the press.

When the elevator descends to the one-half package position above total down, the bottom of the lower package on the elevator opens limit switch 156 in the elevator up circuit. As the elevator reaches total down position as described in the preceding paragraph, a lug 158 on the top of the elevator chain changes limit switch 160 from the down circuit to the up circuit. However, the elevator up circuit is not completed, since limit switch 162 in the up circuit is open while the stack of packages moves out of the left side of the elevator. When the stack of packages has passed over limit switches 156 and 162, the elevator drive up circuit is completed and the elevator rises until the lug 158 on the top of the elevator chain changes the circuit from up to down in limit switch 160.

As previously described, a pusher bar assembly 118 is mounted on the floor of the elevator bed between the conveyors 74. As the elevator comes to rest at its total down position, solenoid air valve 164 is energized by limit switch 156 which is contacted by the lowermost package when the elevator is in its complete down position. The energizing of solenoid valve 164 admits air to the air cylinder 131 mounted on the elevator bed. The piston 134 with double sheave 132 on its free end is extended, and by means of the cable arrangement previously described, pusher bar 126 is moved transversely across the elevator platform transporting the stack of packages to the side delivery conveyors 138 located in a common plane with the elevator platform when the elevator is in its complete down position. As soon as the up circuit is completed, and the elevator rises from contact with limit switch 166, the pusher bar assembly is returned to its retracted position at the side of the elevator platform.

While the machine of the present invention is particularly adapted for operation in connection with a wrapping machine as described in my co-pending application Serial No. 198,711, it is, of course, capable of operating satisfactorily wherein the wrapped packages are delivered in any manner. It is to be understood that such variations in the machine herein shown and described as within the skill of a mechanic may be made without departing from the spirit and scope of the invention.

I claim:

1. Apparatus for stacking wrapped packages of sheet material such as plywood and the like comprising an elevator to receive said packages in superimposed relation, drive means for said elevator, means for applying top pressure to said packages after being received on said elevator, bars mounted for inward movement toward the packages for applying pressure to the sides and ends of said packages on said elevator and means

for discharging the stack of packages when a predetermined number of packages has been received on said elevator.

2. Apparatus for pressing and stacking wrapped packages of sheet material such as plywood and the like comprising an elevator, drive means for said elevator, means for delivering the packages of sheet material to said elevator, means responsive to the movement of the packages into and out of said elevator to control the rate of descent and the return of said elevator to its total up position, bars mounted for inward movement toward the packages to apply heat and pressure on said package at the time of its deposition on said elevator, said bars acting in response to control means in the path of said package.

3. A press and stacker assembly for handling wrapped packages of sheet material comprising an elevator for receiving said packages from a wrapping machine or the like, means for delivering said packages to said elevator, means responsive to the movement of said packages for lowering said elevator the depth of one package as each succeeding package is delivered to said elevator, means responsive to the movement of said packages for delivering pressure to the top edges of each of said packages as said package is deposited on said elevator and lowered the depth of one package, bars mounted for inward movement toward the packages for applying side and end pressure and heat to said package while on said elevator, whereby proper sealing of the freshly wrapped package is insured.

4. Apparatus as claimed in claim 3 wherein the application of pressure and heat to the sides and ends of said package is responsive to control means in the path of said package as it is moved into said apparatus.

5. A press and stacker assembly for handling wrapped packages of sheet material such as plywood and the like comprising an elevator for receiving said packages in superimposed relation, a pair of receiving rails disposed above said elevator conveyors to deliver said packages to said receiving rails, side and end pressure bars responsive to limit switches in the path of said packages, top pressure applying members normally out of contact with said package but movable into contact with the upper surface of said package as said elevator is lowered to receive an additional package from said receiving rails.

6. A press and stacker assembly for pressing and stacking wrapped packages of sheet material, comprising a pair of parallel package receiving and supporting rails, means for delivering said packages to said rails, means for stopping the forward motion of said package on said rails, a conveyor-elevator disposed beneath said rails, means for laterally displacing said rails when the forward motion of said package is stopped whereby said package is permitted to drop down upon said elevator, means for lowering said elevator the depth of one package after said package drops down upon said elevator, means for applying pressure to the top edges of the upper package on said elevator as said elevator is being lowered, and means for laterally discharging the stack of packages from said elevator upon said elevator reaching its lowermost level.

7. A press and stacker assembly as claimed in claim 6 wherein said package receiving rails are integral and movable with a pair of side presser bars, said presser bars having a plurality of strip heaters disposed thereon.

8. A press and stacker assembly as claimed in

claim 7 wherein a series of limit switches are disposed in the path of said moving package to control the movement of said rails, said elevator, and said top pressure applying means.

9. A press and stacker assembly as claimed in claim 6 which includes end pressure applying bars having a series of strip heaters disposed thereon.

10. A press and stacker assembly for handling wrapped packages of sheet material comprising means for individually receiving said packages, an elevator to receive said packages from said receiving means in superimposed relation, lowering means for said elevator, and means for discharging said packages from said elevator when a predetermined number of packages has been deposited thereon, means for simultaneously applying heat and pressure to the sides and ends of each of said packages from end to end thereof prior to its being discharged from said elevator, means for returning said elevator to its raised position upon discharge of said packages.

11. A press and stacker assembly for handling wrapped packages of sheet material comprising a pair of spaced supporting members to individually receive the wrapped packages, upper and lower conveyors to deliver said wrapped package to said supporting members, a wax dispenser mounted above said moving wrapped package so as to deliver powdered wax to the upper surface thereof, a bumper bar assembly de-limiting the forward motion of said package on said supporting members, an elevator having a series of transverse conveyors on the upper surface thereof, drive means for said elevator, means for displacing said supporting members from beneath said package permitting said package to drop to said elevator, means for lowering said elevator the depth of one package upon said package being deposited thereon, top pressure applying means mounted above said package, means for moving said top pressure means into contact with the upper edges of said package as said elevator is descending, a pusher element mounted on said elevator in position to contact the lowermost package on said elevator and transfer the stack of packages on said elevator to a set of receiving rollers on a level with said elevator when said elevator is fully descended.

12. A press and stacker assembly as claimed in claim 11 wherein said pair of spaced supporting members comprise parallel rails integral with a pair of side presser plates, with said rails and presser plates being so dimensioned to permit the reception of a package on said supporting rails while said presser plates are applying pressure to the sides of the uppermost package on said elevator.

13. A press and stacker assembly as claimed in claim 11 wherein said wax dispenser comprises a hollow, freely rotatable, counterweighted roll having at least one perforation in its outer periphery at a point spaced from said counterweight, with said roller being rotated by means of frictional contact with the upper surface of the moving package being delivered to said press and stacker.

14. A press and stacker assembly as claimed in claim 11 wherein said bumper bar assembly is adjustably mounted whereby the length of package which may be handled can be varied.

15. A press and stacker assembly as claimed in claim 11 wherein said rails are integral with a pair of side presser plates, pivotally mounted members supporting said rails and presser plates, a series of link members pivotally connecting

the free ends of said supporting members to opposite ends of a first series of rotatably mounted rocker arms, a rotatable shaft to which said rocker arms are secured, a second series of rocker arms extending above said first series, air cylinders pivotally mounted on said assembly and having their associated piston rods pivotally connected to the free ends of said second series of rocker arms whereby said rails and presser plates may be laterally displaced upon actuation of said pistons.

16. A press and stacker assembly as claimed in claim 11 having end pressure plates for said package and side pressure plates, said pressure plates acting to exert pressure on the sides of said package upon being dropped to said elevator, means for applying heat to the sides and ends of said package while pressure is applied by said pressure plates.

17. A press and stacker assembly for handling wrapped packages of sheet material and the like comprising a series of upper and lower spaced conveyors to receive said packages from a wrapping machine or the like, means for applying wax to the upper surface of said packages while passing through said conveyors, a pair of pivotally mounted spaced rail members to receive said package from said conveyors, an elevator assembly disposed beneath said rails, drive means for said elevator responsive to the movement of said package, means responsive to the movement of said package on said rails to pivot said rails away from said package permitting said package to drop down onto said elevator, means actuated by the movement of said package for lowering said elevator the depth of one package as said package if deposited thereon, top pressure bars mounted above said elevator, means actuated by the movement of said package for extending said top pressure bars into contact with the upper surface of said package as said elevator is descending the depth of one package, side and end pressure plates movable into contact with the sides and ends of said package in response to the movement of said package from said rails to said elevator, a pusher bar assembly actuated by means responsive to the movement of said elevator and the packages thereon to discharge said packages from said elevator when a predetermined number has been stacked thereon.

18. A press and stacker assembly as claimed in claim 17 wherein said rails and top and side presser bar actuating means comprise air pistons and cylinders, with the air supply to said cylinders being controlled by solenoid valves responsive to limit switches positioned so as to have proper sequential contact with the moving package.

19. A press and stacker assembly as claimed in claim 17 wherein said pusher bar assembly is actuated by an air cylinder and piston with a solenoid air valve controlling the delivery of air to said cylinder, and a series of limit switches movable by contact with said elevator assembly and the packages stacked thereon to control said solenoid air valves.

RAY C. DEMLER.
